DENTISTS' GOLD-RECOVERING DRAIN
ATTACHMENTHarold Rush Hall, Cleveland Heights, and George
Washington Conner, Cleveland, Ohio

Application August 4, 1937, Serial No. 157,300

3 Claims. (Cl. 209—41)

The present invention relates to an attachment adapted to be quickly and easily inserted into and removed from a drain opening through which gold and similar precious metals are likely to be carried by the drainage stream.

The device embodying the principle of our invention, although generally adaptable to be used in drains and drain outlets through which precious metals are likely to be passed, is particularly adapted to use in the practice of dentistry where gold, silver and other valuable metals, in the form of filings, dust and minute grinding and abrasive particles, are washed down the drain of a dental cuspidor or sink.

The general object of our invention is to provide such an attachment which can be readily inserted and removed from the drain opening and includes means for directing the drainage stream through a receptacle or container in which there is located a material such as mercury or mercury amalgam, which will readily occlude or alloy with the gold, silver and the like; and which receptacle or container can easily be removed from time to time from the drain, with the recovered gold. A further object of our invention is to provide means for reversing the flow of the drainage stream as it passes through the gold recovering receptacle; so that the force of gravity can be utilized to augment the separating and recovering action of the heavier particles of gold and the like.

To the accomplishment of the foregoing and related ends, said invention, then, consists of the means hereinafter fully described and particularly pointed out in the claims, the annexed drawing and the following description setting forth in detail certain structure embodying the invention, such disclosed means constituting, however, but a few of various structural forms in which the principle of the invention may be used.

In said annexed drawing:—

Fig. 1 is a vertical sectional view taken through a device embodying the principle of my invention; and Fig. 2 is a fragmentary detailed, sectional view showing an alternative form of attachment of the mercury container to the outer tubular member.

Now referring more particularly to the drawing, there is shown in dotted lines therein the bottom portion 1 of a dental cuspidor or sink having a drain opening 2 to which there is attached the down-pipe or drain-pipe 3. A cylinder or tubular member 4 having an outer diameter less than the inner diameter of the drain-

pipe 3 is adapted to fit within the latter and within the drain opening 2 by means of the provision of the outwardly curved and flared top portion 5. A funnel-shaped member 6 fits within the outwardly flared wall portions 5 and carries a central tube 7 which is spaced from the inner walls of the tubular member 4 and leads to the bottom portion of the latter. A receptacle or container 8 composed of a non-metallic material such as glass is removably secured and sealed to the inner walls of the tubular member 4 by means of a sealing gasket or ring 9 composed of resilient material such as rubber. The glass container may be alternatively attached to the larger tubular member as shown in Fig. 2, wherein the glass container 28 has a recessed marginal rim 29 adapted to engage with the punched out ribs or lugs 30 on the outside of the larger tubular member 24. Slots 31 are provided in the top of the rim 29 so that the container 28 can be moved past the lugs 30 and then rotated to hold the latter on the end of the tubular member 24 in the manner of a bayonet lock. In this last described construction, the smaller tubular member 27 is of course continued down below the end of the outer tubular member 24.

A quantity of liquid material, such as mercury or mercury amalgam which has an affinity for alloying or occluding gold, silver and similar precious metals, is contained in the receptacle 8. A screen ring 12 is located just above the top of the receptacle 8 and in the space between the tube 7 and the outer tubular member 4. Baffle plates 13 and 14, which are in the form of rings, are attached to the walls of the tubular member 4 and the tube 7 respectively, and extend through the space between the latter two elements. The baffle plates 13 and 14 are composed of an amalgam, such as an alloy of copper and mercury, and are preferably removably attached to the walls of the tubular member 4 and tube 7 by means of a close fit, so that they may be removed and reinstalled from time to time merely by forcing them out through the bottom ends of the tube 7 and tubular member 4 respectively. Outlet openings 15 are provided in the wall of the tubular member 4 adjacent the top of the tube 7 and just below the bottom of the funnel-shaped member 6.

The operation of the above described device is as follows:—

The drainage stream enters the funnel-shaped member 6 where it is conducted down through the tube 7 and thence into the receptacle 8. As will be seen in the drawing, the lower end of the

tube 7 extends slightly below the liquid level of the mercury or mercury amalgam 10. As the drainage stream passes through the receptacle 8 and through the material 10 contained therein, its direction of flow is reversed from downward to upward, as indicated by the arrows. In this manner the force of gravity tends to throw out the heavier particles such as gold and the like entrained in the drainage stream, so that 10 the latter are retained in the receptacle 8. The drainage stream then proceeds in an upward direction in the space between the tube 7 and the outer tubular member 4 passing the screen 12 and the baffles 13 and 14, which latter elements function to make the drainage stream turn at right angles as it flows in an upward direction above the top of the receptacle 8, whereby any additional heavier particles which might still be entrained in the drainage stream have an opportunity to settle down towards the receptacle 8. 15 The screen 12 serves the additional function of further supporting and locating the bottom portion of the tube 7 with respect to the outer tubular member 4. The drainage stream finally 20 passes through the outlet openings 15 into the drain pipe 3.

From time to time, say, at intervals of a week or so, the above described device may be simply removed from the dental cuspidor or sink 1, 25 merely by lifting it up out of the drain pipe 3. The receptacle 8 can then be withdrawn from the bottom of the tubular member 4 and its contents removed and sent to an assay office or similar agency. A new supply of mercury or mercury amalgam 10 is again placed in the receptacle 30 8, the latter inserted into the bottom of the tubular member 4 which in turn is again inserted into the drain 2. The baffle plates 13 and 14, composed of mercury amalgam, are also removed 35 from time to time, since they will also collect particles of gold and precious metal which is not retained in the receptacle 8 and which might escape past the latter.

It will thus be seen that my above described 40 invention provides an extremely convenient, easy to operate, and inexpensive means for recovering gold and other precious metals which would otherwise become lost and carried away with other waste material by the drainage stream. 45 Due to the fact that my device can be simply dropped into the drain outlet or opening of a cuspidor or sink, and will fit into various sizes of such outlets due to the provision of the flared end portion 5, it will be seen that no additional 50 attachment means such as fasteners, threaded connections or adaptors are required.

Other modes of applying the principle of my invention may be employed instead of the one

explained, change being made as regards the structure herein disclosed, provided the means stated by any of the following claims or the equivalent of such stated means be employed.

We therefore particularly point out and distinctly claim as my invention:

1. A drain attachment for recovering gold and similar precious metals from dental cuspidors and the like, comprising a tubular member adapted to be removably inserted in said drain, 10 a receptacle in said member for material having an affinity for gold and precious metals, a tube spaced from and located within the walls of said member, said tube leading from the top to the bottom of said member and having its lower end terminating in said receptacle, an outwardly flared upper end on said member for engaging with the end of said drain, and a funnel-shaped member carrying said tube and fitting against 15 said flared upper end.

2. A drain attachment for recovering gold and similar precious metals from dental cuspidors and the like, comprising a tubular member adapted to be removably inserted in said drain, 20 a removable, non-metallic receptacle mounted in the bottom of said member, material having an affinity for gold and precious metals contained in said receptacle, an outwardly flared upper end on said member for engaging with the end of said drain, a funnel-shaped member fitting 25 against said flared upper end, a tube carried by said funnel-shaped member and spaced from and located within the walls of said tubular member, said tube leading from the top to the bottom of said tubular member and having its lower end terminating in said receptacle.

3. A drain attachment for recovering gold and similar precious metals from dental cuspidors and the like, comprising a tubular member adapted to be removably inserted in said drain, 30 a removable, non-metallic receptacle mounted in the bottom of said member, material having an affinity for gold and precious metals contained in said receptacle, an outwardly flared upper end on said member for engaging with the end of said drain, a funnel-shaped member fitting against 35 said flared upper end, a tube carried by said funnel-shaped member and spaced from and located within the walls of said tubular member, said tube leading from the top to the bottom of said tubular member and having its lower end terminating in said receptacle, and outlets in the walls of said tubular member located adjacent the upper end of said tube and below said funnel-shaped member.

HAROLD RUSH HALL,
GEORGE WASHINGTON CONNER.
